PLUMBING FIXTURE

Application filed April 3, 1929. Serial No. 352,271.

This invention relates to plumbing fixtures.

The invention particularly relates to back pressure traps in which the flow of fluid through the trap is confined to a predetermined direction and back flow or back pressure is prevented.

It is among the objects of the present invention to provide a plumbing fixture in which a buoyant float is adapted to control the movement of a valve with respect to its valve seat.

It is a further object of the present invention to provide a buoyant float in combination with leverage means for controlling the movements of an associated valve.

A further object of the present invention is to provide a back pressure trap in which the valve and controlling float therefor are received when in open position out of the path of fluid flow, whereby the rate of flow of fluid through the fixture will not be impeded.

Other important objects of the present invention include the combination and interrelation of parts whereby the whole forms a novel, improved and efficient structure well designed to meet the demands of economic manufacture.

Other objects and features of the present invention will be apparent from a consideration of the following specification taken in conjunction with the accompanying drawings, in which.

Figure 1 is a longitudinal section illustrating one form of the present invention;

Fig. 2 is a sectional view taken through lines 2—2 of Fig. 1;

Fig. 3 is a detail of one preferred form of valve mounting.

Referring more particularly to the drawings, the present invention has been disclosed in association with a straightway plumbing fixture, including a body 10, inlet end 11 and outlet end 12, the inlets and outlets being arranged for soldered connection with associated fixtures.

It will be understood that the present invention is in no way confined to the specific plumbing fixture herein disclosed and that

the valve assembly may be associated with various types of fixtures arranged for either soldered or threaded interrelation and that it may be associated with P fixtures, 90° L's, offsets, vertical and horizontal fixtures, together with manhole covers and ferrule type fixtures. It will be understood that modifications of the structural features herein presented to conform the invention to various specific types of fixtures, do not depart from the spirit or scope of the present invention.

Referring particularly to Fig. 1 of the drawings, the body 10 of the straightway fixture illustrated is preferably provided with an extended housing 13, adapted to lie above the body of the fitting and to provide a space for the reception of the valve and valve float out of the path of travel of the fluid passing through the fixture. The housing 13 is preferably provided with a readily removable cover 14, which may be secured thereto through suitable nut-and-bolt assemblies 15, the arrangement being such that access to the fixture and the valve assembly mounted therein may be readily had.

Pivotedly mounted within the fixture to be normally received within the housing 13, a float 16 is provided, which is illustrated as circular and substantially flat and is preferably formed of metal or the like, and may, if desired, be filled with helium gas or other buoyant substance, the arrangement being such that should the fluid within the fixture be blocked from passage therethrough and the level of the fluid rise within the housing 13, the float 16 will be buoyed up to the dotted-line position shown in Fig. 1. It will be understood that the structure and material from which the float is formed, may be widely varied, and, if desired, a simple hollow rubber float may be utilized.

For mounting the float for pivotal movement with respect to the housing 13, a substantially U-shaped member is provided including a base 17 and parallel extending arms 18. The float 16 is arranged preferably for pivotal movement with the base 17, a preferred attachment being illustrated by the eyelets 19 associated with the float 16,

through which the base 17 is mounted. For pivotally mounting the U-member within the housing 13, parallel intermediate portions of the arms 18 are associated with a transversely extending fulcrum arm 20, the extremities of which are mounted for pivotal movement within apertures 21 of adjustable threaded members 22 which are threadedly secured through the side walls 5 of the housing 13. The intermediate portions of the arm 18 may be either rightly associated with the fulcrum 20 or may be loosely mounted thereon. In either instance, free pivotal rotation of the arms 18 in response to the buoyancy of the float 16, is accomplished.

Associated with the float and U-member, a suitable valve 23 is provided, the valve being illustrated as a disk valve of frustoconical formation adapted to be received when in closed position as indicated in Fig. 1, against a suitable valve seat 24. The valve seat 24 is shown as formed of suitable resilient material and secured with 20 in its receiving recess by an expanding metallic ring 25. The valve 23 is preferably formed of metal well adapted to resist corrosion or the like. It will be understood, however, that if desired the 25 valve 23 may be formed entirely or in part of resilient material and the resilient valve seat replaced by a simple metallic surface against which the valve may seat. It will be seen that the invention is, therefore, not confined to specific materials employed in the valve or in the valve seat.

For moving the valve 23 in response to movements of the float 16, the extremities of the arms 18 are enlarged as at 26, and 40 provided with arcuate apertures 27 which are adapted to receive therethrough angularly terminating fingers 28 carried upon a transversely extending valve fulcrum rod 29. The fingers 28 are preferably provided with 45 suitable rollers 28' which prevent undue friction between the parts. The rod 29 is mounted for pivotal movement within the housing 13 by apertured threaded members 30, the mounting being preferably substantially similar to the mounting of the fulcrum arm 20. The connection between the arms 18 and the fulcrum rod 29 by means of the fingers 28, is such that upward movement of the float 16 will cam downwardly 50 the extremities of the fingers 28, thus pivotally moving the valve 23 downwardly to contact with its seat, the position of the float, the U-member and the valve when seated, being indicated by the dotted lines 55 in Fig. 1.

For mounting the valve 23 for movement with its fulcrum rod 29, lugs 31 are provided mounted for rotation with the rod 29. Extending from the lugs 31, arms 32 are 60 provided which terminate in externally

threaded extremities which are adapted for threaded engagement with suitable balls 33. The arrangement may be clearly seen by reference to Fig. 3 of the drawings. The balls 33 are received within suitable housings 34 70 carried by the valve 23. The housings 34 are preferably secured on the valve 23 by soldering or similar connection, and include a pair of side apertures 35 through which the ball 33 may be inserted before threaded 75 engagement with the arm 32. Surrounding the arm 32 and abutting the lugs 31 and the housing 34, an expansion spring 36 is provided, the arrangement being such that a ball-and-socket joint is provided between the 80 arms 32 and the valve 23. The ball-and-socket joint is at all times under the pressure of the spring 36. However, slight relative movement of the valve 23 is provided for so that in seating it may readily accommodate for wear. Should through wear or accident of the various parts, the valve be caused to seat out of alinement with its normal support from its fulcrum rod 29, the spring 36 may be compressed and the ball 33 90 may be received within the housing 34 in the position indicated in Fig. 3.

In the operation of the present invention, it will be seen that during the normal flow of fluid from the inlet to the outlet of the fixture, the float 16 is in the lowered position shown in Fig. 1. Thus the valve 23 is pivotally moved upwardly permitting free passage of fluid through the valve seat and being received within the housing 13 whereby 95 neither the float nor the valve restricts the passage of fluid through the fixture. Should, however, the passage of fluid be blocked, back pressure will be exerted and the fluid level will raise into the housing 13 whereby 100 the float 16 will be buoyed up to the position shown in dotted lines in Fig. 1 and as described the U-member will be pivotally moved to rotate the valve fulcrum arm 29, thus moving the valve to the closed position 105 whereby back pressure further back through the system will be prevented.

From the foregoing it will be readily seen that the present invention provides a simple and efficient structure which may be arranged in various types of fittings without retarding the flow of fluid therethrough.

It will be understood that numerous changes and modifications in the materials employed and in the structural details herein presented may be resorted to without departing from the spirit or scope of the present invention as outlined in the appended claims.

What is claimed is:

1. A plumbing fixture, including a valve and valve seat, and buoyant means for controlling the movement of said valve, said means including a float and an associated leverage system between said float and said

valve, said leverage system including a U-member intermediately pivoted to said fixture.

2. A plumbing fixture, including a valve and valve seat, and buoyant means for controlling the movement of said valve, said means including a float and an associated leverage system between said float and said valve, said leverage system including a U-member intermediately pivoted to said fixture, the base of said U being associated with said float.

3. A plumbing fixture, including a valve and valve seat, and buoyant means for controlling the movement of said valve, said means including a float and an associated leverage system between said float and said valve, said leverage system including a U-member intermediately pivoted to said fixture, the base of said U being associated with said float, the arms of said U being arranged with said valve for controlling the movement thereof.

ALBERT M. KHUN.
